UNITED STATES PATENT OFFICE.

HENRY ERNST PAUK, JR., OF ST. LOUIS, MISSOURI, ASSIGNOR TO THE HENRY PAUK & SONS MANUFACTURING COMPANY, OF SAME PLACE.

SANDPAPERING-MACHINE.

SPECIFICATION forming part of Letters Patent No. 541,878, dated July 2, 1895.

Application filed October 8, 1894. Serial No. 525,240. (No model.)

To all whom it may concern:

Be it known that I, HENRY ERNST PAUK, Jr., a citizen of the United States, and a resident of St. Louis, in the State of Missouri, have invented certain new and useful Improvements in Sandpapering-Machines, of which the following is a full, clear, and exact description, reference being had to the accompanying drawings, forming a part hereof.

10 This invention relates to improvements in that class of machinery known as sand papering machines, and has for its objects to enable moldings and other irregular surfaces to be sandpapered, to readjust the sand paper 15 in its holder when worn, without causing ridging or unevenness of the work which occurs when the paper is sectionally glued together, and to regulate the pressure on the work for insuring perfect smoothness of surface.

20 The invention consists in features of novelty hereinafter described and claimed, reference being had to the accompanying drawings, forming part of this specification, whereon—

25 Figure 1 is a front elevation of my improved sandpapering-machine. Fig. 2 is a plan thereof. Figs. 3 and 4 are opposite end views of the machine. Fig. 5 is a rear elevation thereof. Fig. 6 is a transverse section taken on line 6 6 in Fig. 5. Fig. 7 is a cross-section to enlarged scale of the sandpaper-holder as seen in Fig. 6, detached. Figs. 8, 9, 10, 11, 12, 14, and 15 are cross-sections to enlarged scale of the beds or bearing-rails for supporting and 30 guiding various forms of moldings to be sandpapered, and Fig. 13 is a horizontal section through the sandpaper-holder, taken on line 13 13 in Fig. 7. Fig. 16 is a side elevation of the sandpaper-holder to an enlarged scale, 40 showing the pawl and ratchet wheel. Fig. 17 is an enlarged sectional view of the adjusting mechanism for the bead-plate.

Like letters and numerals of reference denote like parts in all the figures.

45 A. represents the framework of the machine having the table b, through which, parallel to its front edge is a gap c extending the entire length of the table b. On the table b, and across the gap c, is mounted a preferably rectangular frame d having a central opening d'

which is located immediately over the gap c. The frame d is preferably held in position on the table b by four bolts or vertical guides e which are fixed at their lower ends by nuts f, or otherwise, to lugs g in the framework A, 55 and project upward therefrom, passing freely through the frame d to a suitable distance above the latter, the free ends of the bolts e being provided with shoulders h and connected together by bracing i, as shown. 60 Around the bolts e between the frame d and shoulders h, are spiral springs j, which normally tend to press the frame d downward toward the table b. To the frame d, preferably at each side, are fixed depending rods k, 65 which pass through guides l fixed to the framework A, for guiding the frame d when raised from, or lowered to, the table b, as hereinafter more particularly referred to.

On the framework A, preferably near one 70 end thereof, and in rear of the gap c, are standards A', which are arranged opposite to each other, transversely to the table b, and carry bearings m through, and between which, is mounted the driving shaft n of the machine. 75 To the front end of the shaft n, which projects beyond the front bearing m, is fixed a face plate o having a crank pin p which is connected by a rod or pitman q to the sand paper holder r, the pitman q and holder r being located preferably in the central vertical plane of the gap c. The holder r is composed (see particularly Figs. 7 and 13) of a preferably rectangular box or frame s, having its ends 1. 1. projecting somewhat beyond the sides 2. 2. 80 Across the front and rear projecting upright edges of the ends 1. 1. are V-shaped grooves t which are adapted to slide along the correspondingly shaped edges 3. 3. of the opening d' in the frame d. Within the frame s is 85 placed a block u of cork, rubber, or like material which partly projects below the frame s and is shaped transversely on its under side to conform to the configuration of the molding or material to be sand papered. The 90 block u is held in longitudinal alignment with the pitman q by two plates v which are arranged vertically and adapted to slide transversely within the frame s, one on each side of the block u, the latter being clamped be- 95 roo

tween the sliding plates *v* by set screws *w* which work through the sides 2.2 of the frame *s* and bear at their inner ends against the plates *v*. The plates *v* are preferably grooved at their ends and supported thereby within the frame *s* on ledges 4.4, projecting from the insides of the ends 1.1.

Above the block *u*, in parallel alignment therewith, is a roller *x*, which is axially mounted in bearings *y* carried on the ends 1.1, of the frame *s*, the roller *x* being operated by the handle *z* and provided with a ratchet wheel *a'* which is engaged by the pawl *a*. Around the roller *x* is wound a strip of sand paper *b'*, the free end of which passes downward through the opening in the frame *s* on the outside of one of the plates *v*, and thence across the under side of the block *u*, and upward through the opening in the frame *s* on the outside of the other plate *v*, the sand paper *b'* being held in this position by two plates *c'* which are arranged parallel to the plates *v* within the frame *s*, externally to the sand paper *b'*, and clamp the latter against the plates *c'* respectively, by means of set screws *d* which work through the sides 2.2. of the frame *s*, and bear at their inner ends against the plates *c'*. The plates *c'* are supported within the frame *s* by the set screws *w* which pass freely through holes, 5. in the plates *c'* as shown.

By the above arrangement, on slackening the plates *c'* and partly unwinding the sand paper strip *b'* from the overhead roller *x* the worn portion of the sand paper *b'* where it crosses the under side of the block *u* can be continuously removed, and a fresh surface free from glued joints adjusted thereto, until the paper roll is exhausted.

Beneath the gap *c* in the table *b* is a trough 40 or channel *e'* (which is preferably made of wood, or other material) removably fixed to, and extending the entire length of the table *b*. Along the bottom of the trough *e'* is fixed a bed or bearing rail *f'*, having its upper face 45 conformable in cross section to the configuration of the under side of the molding *g'*, which is supported on, and caused to travel along, the bar or rail *f'* by preferably double feed rollers *h'* (one roller *h'* at each end, or thereabout, of the machine) which are fixed on shafts *i'* mounted transversely to the machine in suitable bearings, and rotated by any suitable mechanism. Each roller *h'* projects through, and slightly above, the adjacent central portion of the bed or rail *f'*, and is serrated transversely on its circumference, so that, on the rotation of the rollers *h'* a firm hold is taken on the under side of the molding *g'* and the positive movement of the latter along the bed or rail *f'* thereby insured.

Bearing upon the upper side of the molding *g'*, immediately over the feed rollers *h'*, are idler rollers *j'* which conform to the configuration of the molding *g'* and are axially mounted 65 in bearings *k'*, which are vertically adjustable for maintaining a normal pressure of the

molding *g'* against the feed rollers *h'*, according to the varying thicknesses of the material to be sand papered. If desired one, or more, intermediate idler rollers *j'* may be used for 70 guiding and maintaining the proper alignment of the molding *g'*, as shown in Fig. 2.

For reciprocating the sand paper holder *r*, and rotating the feed rollers *h'*, a pulley *l'* is preferably fixed on the driving shaft *n* and 75 driven by belt from any suitable power. The pulley *l'* is provided with the loose pulley *l* and belt shifter *b* in the usual manner.

On the rear end of the shaft *n* is fixed the varying speed pulley *m'* which is connected 80 by the belt *n'* with a corresponding pulley *m* fixed on the shaft *i'* carrying one of the feed rollers *h'*, and on the same shaft *i'* is fixed a pulley *o'*, which connects by belt *p'* with a corresponding pulley *o* fixed on the shaft *i'* 85 of the other feed roller *h'*.

To the under side of the frame *d*, near each end thereof, are attached the forked ends of a depending bar *q'* which is coupled at its lower end to the inner arm of a lever *r'* pivoted to 90 the framework *A*, the outer arms of the levers *r'* being connected together by a treadle bar *s'* in front of the machine, whereby on depressing the treadle *s'* the frame *d* with the sand paper holder *r* and its appendages may 95 be raised from the table *b* against the pressure of the springs *j* at pleasure. When raised to its full extent, as indicated by dotted lines in Figs. 1, 5, and 6, a lever *t'* which is pivoted to the framework *A* swings by the superior 100 gravity of its longer arm, beneath the frame *d* and thereby supports the latter in the raised position as long as desired; or the frame *d* may be raised and lowered by any other suitable arrangement of mechanism.

In operation, assuming the frame *d* and holder *r* with the sand paper *b'* fixed therein, to be raised and supported as described, and the molding *g'* properly adjusted along its bed or rail *f'*, and between the rollers *h', j'*, 110 on releasing the lever *t'* and lowering the frame *d* to within a short distance from the table *b*, the sand paper *b'* bears upon the molding *g'* and is thereby pressed into the depressed portions or corresponding configuration of the 115 under side of the block *u* which tightens the sand paper *b'* thereat, and causes it to bear thoroughly against every part of the molding *g'*. Rotation being then given to the crank disk *o, p* so as to reciprocate the holder *r* by 120 the pitman *q* the sand paper *b'* is moved to and fro on the molding *g'*. Simultaneously, by the rotation of the feed rollers *h'*, the molding *g'* is moved slowly along its bed or rail *f'* toward the delivery end of the machine 125 so as to continually present a fresh surface to the rubbing action of the sand paper *b'* until the operation is completed.

For starting and stopping the feed movement of the molding *g'* at pleasure during the 130 sand papering process, an idler roller *u'* is located over, and transversely to the driving

belt n' , the spindle or axis of the roller u' being fixed part way along, and at right angles to, a vertically arranged arm or lever v' which is hinged at its lower end to the framework A and provided at its upper, or free end with a handle w' , so that on throwing the lever v' over on its fulcrum in one direction the roller u' bears by gravity upon the belt n' which is thereby tightened and rotates the feed rollers h' for starting the molding g' , and by throwing the lever v' over in the opposite direction the roller u' is removed from the belt n' which becoming slackened ceases to rotate the feed rollers h' and thereby stops the movement of the molding g' . For more perfectly adjusting the pressure of the sand paper b' upon the molding g' , a screw threaded bolt α' bears at its upper end against the under side of the frame d (at each side thereof) and works through a worm wheel or nut y' which is held by, and between the jaws of a bifurcated bracket z' fixed to the framework A. The worm wheels or nuts y' are engaged by worms y^2 fixed on a shaft a^3 which is mounted in suitable bearings carried by the framework A, the shaft a^3 being rotated by a handle b^2 , or other suitable means, so that on rotating the worms y^2 in either direction the bolts x' , and with them the frame d and holder r , are gradually raised or lowered, and the pressure of the sand paper b' on the molding g' increased or diminished accordingly at pleasure. This movement is independent of, and in nowise interferes with, the action of the treadle s' .

35 This invention, which is particularly adapted for sand papering various descriptions of moldings, such as those shown in Figs. 9, 10, 11, 14, and 15, is also applicable for flat work, the bearing rails and sand paper block being adapted in each case to the configuration of the under, and upper sides, respectively, of the material to be operated on.

By this invention, owing to the continuity of the sand paper where it crosses the face of the molding, all glued joints in the sand paper and consequent unevenness or ridging on the surface of the work are avoided. Also by the reciprocating movement of the sand paper along the work in preference to a rotary movement thereon, combined with the means employed for regulating the pressure, the sand papering is more thoroughly and uniformly effected, and a perfectly smooth surface insured.

55 What I claim as my invention, and desire to secure by Letters Patent, is—

1. In a sand papering machine, a holder for the sand paper, comprising a box or frame, having two opposite inner plates held vertically by, and adapted to slide transversely within the frame, means for moving the said plates against an interposed block of flexible material projecting partly below the frame,

two outerly plates intermediate, and parallel to, the inner plates and sides of the frame, respectively, and means for moving the outerly plates toward the inner plates, and against interposed portions of the sand paper, substantially as shown and described.

2. In a sand papering machine, a holder for the sand paper, comprising a box or frame having two opposite inner plates held vertically by, and adapted to slide transversely within the frame, means for moving the said plates against an interposed block of flexible material projecting partly below the frame, outerly plates, intermediate, and parallel to, the inner plates and sides of the frame, respectively, means for moving the outerly plates toward the inner plates and against interposed portions of the sand paper, a roller axially mounted above the frame, and means for winding and holding the sand paper around the said roller, substantially as shown and described.

3. In a sand papering machine, the combination with the holder, and the bed supporting the material to be sand papered, of a holder for the sand paper, composed of a box or frame carrying inner and outerly plates and means for moving the plates against an interposed block of flexible substance, and against interposed portions of the sand paper, respectively, the said holder being adapted to slide on a frame, and means for reciprocating the holder along the said frame, substantially as shown and described.

4. In a sandpapering machine, the combination with the table, and the bed supporting the material to be sandpapered, a vertically adjustable frame mounted upon said table, and provided with guides, springs bearing upon the frame, a holder for sand paper, composed of a box or frame carrying inner and outerly plates and means for moving the plates against an interposed block of flexible material and against interposed portions of the sand paper respectively, the said holder being adapted to slide on the said vertically adjustable frame, and means for reciprocating the holder along the said frame, substantially as shown and described.

5. In a sand papering machine, the combination with the framework, of a vertically adjustable frame provided with guides and adapted to carry the sand paper holder, springs bearing upon the frame, means for raising the frame against the pressure of the springs, and pivoted levers adapted to swing beneath and support the frame when raised, substantially as shown and described.

6. In a sand papering machine, the combination with the framework, and the bed supporting the material to be sand papered, of a vertically adjustable frame, provided with guides and adapted to carry the sand paper

holder, screwed bolts bearing against the under side of the frame and working through worm wheels or nuts held in fixed brackets, the wheels or nuts being engaged by worms 5 fixed on a shaft, and means for rotating the said shaft, substantially as shown and described.

In testimony whereof I affix my signature in the presence of two witnesses.

HENRY ERNST PAUK, JR.
